UNITED STATES PATENT OFFICE.

GEORGE W. NELSON, OF CLEVELAND, OHIO, ASSIGNOR TO THE STANDARD SEWING MACHINE COMPANY, OF CLEVELAND, OHIO, A CORPORATION OF OHIO.

SEWING-MACHINE.

1,357,468.

Specification of Letters Patent.

Patented Nov. 2, 1920.

Application filed September 24, 1919. Serial No. 325,887.

To all whom it may concern:

Be it known that I, GEORGE W. NELSON, a citizen of the United States, and resident of Cleveland, in the county of Cuyahoga and State of Ohio, have invented certain new and useful Improvements in Sewing-Machines, of which the following is a specification.

This invention relates to sewing machines and has particular reference to chain-stitch sewing machines of the class in which successive groups or series of stitches are made at separated points in the work, as for example, in button sewing machines, tag sewing machines, etc. In chain-stitch machines of this class it is customary to sever or break the thread on the completion of each group or series of stitches. This is accomplished in the button sewing machines disclosed in my prior Patents Nos. 1,252,931 and 1,288,652, granted Jan. 8, 1918, and Dec. 24, 1918, respectively, by means comprising a thread-restraining device which is operated upon the completion of a group of stitches to clamp and hold the thread, and a pivoted work-holder which is adapted to be moved in a direction to produce a strain on the thread held by said thread-restraining device and effect a breaking of the same close to the under side of the work.

In these prior machines, the button clamping members of the work-holder are opened horizontally to permit of the insertion and release of the work. In the machine of my present invention, which is particularly adapted for sewing on tags, the work-holder comprises two work-engaging members which open vertically for like purposes. To provide means for causing such form of work-holder to properly coöperate with a thread-restraining device in the thread-breaking operation has been the main object of my present invention. This object I secure by the novel construction, arrangement, and combination of parts embodying my invention as illustrated in the accompanying drawings, in which—

Figure 1 is a rear side elevation, partly in section, of the needle end of a chain-stitch sewing machine equipped with my invention and shows the parts in the positions they occupy during the normal operation of the machine.

Figs. 2 and 3 are details illustrating the operation of the work-holder in its thread-

breaking and work-releasing operations, and

Fig. 4 is a detail, in perspective, of the thread-restraining device on the face plate 60 of the machine.

Similar reference characters indicate like parts in the several figures of the drawings.

The machine here shown, aside from the work-holder, is substantially the same as 65 that illustrated in my said prior Patent, No. 1,252,931, to which reference may be had. It embodies a main frame comprising upper and lower portions, 2 and 3, suitably connected and adapted for the support of the 70 various parts of the operating mechanism. Journaled in the lower portion 3 is the main shaft 4 carrying at its front end a chain-stitch looper 7. For coöperation with this looper in the stitch-forming operation is the 75 usual thread-carrying needle 8, which is carried by the needle-bar 9 mounted for vertical reciprocation in the upper portion 2 of the frame. On the lower portion 3 of the frame adjacent said needle and looper 80 is the work-holder, indicated generally by H, which is adapted to be operated by any usual means to properly present the work to the stitching mechanism.

As hereinbefore stated, machines of this 85 type are operated to make a series or group of stitches, as for example in sewing on a tag, after which the machine is brought to a stop, usually by an automatic stop mechanism. On the stopping of the machine the 90 operator then usually performs the operation of severing or breaking the thread by manually controlled means. This operation is effected by first clamping the thread to restrain or hold it against movement and 95 then moving the work-holder in a direction—upward as here shown—to strain the thread until it breaks, which usually occurs close to the underside of the work.

The restraining device for clamping the 100 thread may be of any suitable type and may be operated either by manual or automatic means. As here shown it is the same in construction and operation as that of my said prior Patent, No. 1,252,931, and comprises fixed and movable clamping jaws, 52 and 53, the former of which is fixed to the face-plate 10 of the machine, while the latter is illustrated as forming part of an angle lever 54 pivoted in a stud 55 on said 105 face-plate. This lever 54 is operatively con-

nected with an actuating rod 46 supported in suitable bearings on the machine frame for longitudinal sliding movement. The rod 46 is automatically controlled through 5 suitable connections from the main shaft whereby it will act upon the completion of a group of stitches to cause the pivoted jaw 53 to coöperate with the stationary jaw 52 and clamp the thread *t* therebetween. As 10 the particular means for actuating the rod 46 does not form a part of my present invention, and as it is fully disclosed in my aforesaid Patent, No. 1,252,931, I have not illustrated or described the same herein.

15 The work-holder here shown comprises a pair of work-engaging members, 75 and 76, which are mounted at their rear ends on a pivot 77. As a means for normally holding this work-holder in its lowered operative 20 position with the upper member in clamping relation to the lower one, a vertical post or stud 78 is attached to the upper member and has a shoulder 79 thereon, in the form of a vertically adjustable nut, between which 25 and the under side of the over-hanging arm 2 is interposed a spring 80, which acts to exert a downward pressure on the work-holder.

As a means for raising the work-holder, 30 that is, swinging the front or work-holding end of the same upward about its pivot 77, the upper member 75 is connected by a suitable connection, such as the chain 81, with the usual operating lever 82, which latter is 35 actuated from a treadle or other like device. Now, in order that the lower member 76 of the work-holder may be caused to move with the upper one when it is being raised, whereby the engaged work may be moved up 40 ward to strain and break the thread—it being understood that the thread extends from said work down around the looper 7 and from thence upward to the restraining device 52—53—a suitable latch is provided for 45 connecting the lower member with the upper one. This latch comprises a pin 83 which is pivoted to the lower member at 84 and extends upward through a slot 85 in the upper member, the same being provided with a notch 86 in one side thereof for latching engagement with the upper member at one edge of its said slot 85, as shown 50 in Fig. 1. A pull spring 87, connecting at one end with the post 78 on the upper member 75 and at its opposite end with the latch pin 83, serves to normally hold the latch in its position of latching engagement with said upper member. With the lower member of the work-holder thus latched to 55 the upper one, it will be clear that both members, with the engaged work, will be moved upward together. When they have been raised sufficiently to effect a breaking of the thread, it is desirable that the two 60 members of the work-holder should be 65

opened to release the work, whereby the latter may be either removed or shifted to a new position for the next sewing operation. To permit such release of the work immediately following the breaking of the thread, I have provided means for automatically releasing the latch at such time, whereby the lower member of the work-holder will move downward from its position of coöperation with the upper one and release 70 the work. This automatic releasing means comprises a stationary arm 88 suitably attached to the upper arm of the frame and having one end thereof, 89, extending into 75 a position at the rear side of the latch pin 80 for engaging and operating the same as follows: When the work-holder is swung upward following the clamping of the thread by the thread-restraining device, the upper end of the latch pin is engaged by the 85 arm 89 and caused thereby to move in a substantially straight line, while the work-holder moves in the arc of a circle described from its pivot 77. This results in the disengagement of the latch from the upper 90 work-holder member 75 at a time following the breaking of the thread, as shown in Fig. 2, wherein the latch is just disengaged from the upper work-holder member. Thereupon the lower member 76 drops to release the work clamped between it and the upper member, as shown in Fig. 3. For causing a quick separation of the work-holder members following the release of the latch, an expansion spring 90 is interposed 100 between said members as shown. Subsequently, upon the lowering of the upper member 75 to its clamping position, the latch pin automatically reengages the same under the action of the spring 87, as shown 105 in Fig. 1.

What I claim is:

1. In a sewing machine, the combination with the stitch-forming mechanism and a thread-restraining device, of a work-holder comprising two work-engaging members, means for moving said members in a direction to break the thread held by said thread-restraining device, and means for automatically releasing one of said members from coöperation with the other following the breaking of the thread. 110

2. In a sewing machine, the combination with the stitch-forming mechanism and a thread-restraining device, of a work-holder comprising two pivoted work-engaging members, means for raising said members to break the thread held by said thread-restraining device, and means for automatically releasing the lower member from coöperation with the upper one following the 115 breaking of the thread.

3. In a sewing machine, the combination with the stitch-forming mechanism and a thread-restraining device, of a work-holder 120

115

120

125

130

comprising two pivoted work-engaging members, means for raising said members to break the thread held by said thread-restraining device, and means operative during the upward movement of the members to automatically release the lower one from coöperation with the upper one following the breaking of the thread.

4. In a sewing machine, the combination with the stitch-forming mechanism and a thread-restraining device, of a work-holder comprising two work-engaging members, means for moving said members in a direction to break the thread held by said thread-restraining device, a latch connecting said members for causing them to move together in their thread-breaking movement, and means for automatically releasing said latch following the breaking of the thread.
5. In a sewing machine, the combination with the stitch-forming mechanism and a thread-restraining device, of a work-holder comprising upper and lower work-engaging members, a latch normally connecting said members, operating means connecting with the upper member for raising both members to break the thread held by said thread-restraining device, and means for automatically releasing said latch following the breaking of the thread.
6. In a sewing machine, the combination with the stitch-forming mechanism and a

thread-restraining device, of a work-holder comprising upper and lower work-engaging members, a latch pin pivoted to the lower member, means yieldingly holding said pin in latching engagement with the upper member, operating means connecting with the upper member for raising both members to break the thread held by said thread-restraining device, and means for automatically releasing said latch pin from engagement with the upper member following the breaking of the thread.

7. In a sewing machine, the combination with the stitch-forming mechanism and a thread-restraining device, of a work-holder comprising upper and lower work-engaging members, a latch pin pivoted to the lower member, means yieldingly holding said pin in latching engagement with the upper member, operating means for raising both members to break the thread held by said thread-restraining device, and a stationary member engaging said latch pin during the upward movement of the work-holder members and operative to release the same from engagement with the upper member following the breaking of the thread.

Signed at Cleveland, in the county of Cuyahoga and State of Ohio, this 3rd day of September, A. D. 1919.

GEORGE W. NELSON.
